UNITED STATES PATENT OFFICE.

JESSE P. HIGBEE, OF LOUISVILLE, KENTUCKY, ASSIGNOR OF ONE-THIRD TO LEOPOLD STOESSER AND ONE-THIRD TO JOHN SULLIVAN, BOTH OF LOUISVILLE, KENTUCKY.

RADIATOR FOR FIREPLACES.

1,297,964.

Specification of Letters Patent. Patented Mar. 18, 1919.

Application filed December 24, 1917. Serial No. 208,580.

To all whom it may concern:

Be it known that I, JESSE P. HIGBEE, a citizen of the United States, residing in the city of Louisville, county of Jefferson, 5 and State of Kentucky, have invented certain new and useful Improvements in Radiators for Fireplaces, of which the following is a specification.

This invention relates to means for increasing the amount of effective heat obtainable from fires in open grate fire places.

The cheer and companionship of an open grate fire is admittedly great but its efficiency is small as the larger proportion of the heat 15 of the fuel goes up the chimney.

An object of this invention is to provide a device, adapted to be positioned in the upper portion of a fire place and projecting outward into the room therefrom, through 20 which the products of combustion pass before they enter the chimney. As the device presents a large radiating surface a greater amount of heat is given out into the room than would otherwise be the case.

25 Other objects are, to provide a device of the character described which shall be economical in construction, pleasing in appearance, efficient in operation and durable in service.

30 With the foregoing and other objects in view, the invention consists of the novel construction and arrangement of parts illustrated in the accompanying drawings, which form a part of this specification, wherein 35 is set forth an embodiment of the invention, but it is to be understood that such changes and modifications may be resorted to as come within the scope of the claims appended hereunto.

40 In the accompanying drawings wherein similar reference characters designate like parts in the several views, Figure 1, is a perspective view of an embodiment of the invention as applied to a fire place. Fig. 2, 45 a top plan view, on an enlarged scale, of the device. Fig. 3, a transverse section. Fig. 4, a longitudinal section on line 4-4 of Fig. 3. Figs. 5 and 6 are elevations respectively of the inside of one head, and the 50 outside of the other head. Figs. 7 and 8 and 9, are respectively a front elevation, end elevation, and transverse cross section of a modified form.

55 Referring now in detail to the drawings, Fig. 1, discloses a structure, designated as

an entirety by the numeral —1—, positioned at the upper portion of a fire place —2—, transversely thereof. The body of the structure comprises a drum —3— extending outward from the fire place into the room. The 60 structure is retained in place by suitable means such as lugs —4— which are connected to the ends of the drum and which may be secured to the frame —5— of the fire place. These lugs may be adjustably 65 connected to the ends of the drum as shown in Figs. 6 and 8. The drum is preferably formed of a continuous length of sheet metal, it comprises an apron —6— disposed at such an angle that it will conform 70 to a fire back —7—, against which it lies when in position. An outer wall —8— of the drum, extends from the upper edge of the wall 6 curving outward, downward and inward to a point —9— within a spaced distance, the apron intermediate its length. From the point 9 an inner wall —10— extends upward in a plane substantially parallel with the apron, the two defining a 75 passage —11—. The wall 10 extends to 80 within a spaced distance of the outer wall 8, from which point an intermediate wall —12— curves downward and inward, in spaced relationship to the outer wall, terminating against the wall 10, to which it is secured. A chamber —13—, into which the 85 passage 11 leads, is defined by the walls 8, 10 and 12. The walls 10 and 12 define an air space or chamber —14—. A partition —15— secured to the wall 8 defines an air 90 space or chamber —16—. The chambers 14 and 16 are open to the atmosphere. A rectangular flue box —17— is secured on the rear side of the wall 10 at a point opposite the end of the chamber 13, and this is adapted 95 to be inserted in the throat —18— of the chimney. A plurality of flues —19— extend from the chamber 13, across the passage 11 into the box 17. The ends of the drum are closed by suitable means such as 100 heads —20—, which are provided with flanges —21, 22, and 23— that serve to confine the walls. Openings —24— and 25— in the heads correspond respectively with the spaces 14 and 16 forming outlets therefrom, for the escape of air which becomes heated therein. When the device is in position the apron lies against the face of the fire back and closes the entrance to the throat of the chimney, consequently the 110

- products of combustion are forced to pass through the passage 11 into the chamber 13 and thence through the flues 19 into the chimney. The draft through the drum may 5 be controlled by means of a damper —26— which is operated by means of an exterior handle 27. In the modification shown in Figs. 7, 8 and 9, a smaller chamber —33— is provided and flues —34— lead from the forward side thereof downward a spaced distance from the front wall —35—, thence rearward through said wall, across the passage 11 and through the apron into the throat of the chimney. It is obvious that 10 my improved drum may be readily applied to the ordinary open grate fire place, and that the large radiating surface which it presents insures greater efficiency in the consumption of fuel.
- 20 Having thus described my invention so that anyone skilled in the art pertaining thereto can make and use the same, I claim:
1. A drum adapted to be positioned at the top of a fireplace, an apron depending therefrom and adapted to cover the throat of the chimney, and having an opening communicating therewith, there being a passage leading from the fireplace to the interior of the drum, and a flue leading from the interior 25
- of the drum across said passage and through 30 said opening, said flue being adapted to be entered into the throat of the chimney.
2. In a device as characterized, a drum adapted to be secured at the top of a fireplace, an apron depending from said drum 35 and adapted to cover the throat of the chimney and having an opening communicating therewith, the drum having a plurality of chambers, one of said chambers being closed and the others open to the atmosphere, there 40 being a passage leading from the fireplace to the interior of the closed chamber, and a flue leading therefrom across said passage and through the opening in the apron, said flue being adapted to be entered into the 45 chimney.
3. In a device as characterized, a drum, means for securing said drum at the top of a fireplace, an apron depending from said drum adapted to cover the throat to 50 the chimney and having openings communicating therewith, the device having a passage leading from the fireplace to the interior of the drum, and a plurality of flues leading from the interior of the drum across 55 said passage and through said apron.

JESSE P. HIGBEE.
